UNITED STATES PATENT OFFICE.

EDWIN LANE, OF NEW YORK, N. Y., ASSIGNOR TO CAROLYN LAUNDRY, OF NEW YORK, N. Y., A CORPORATION OF NEW YORK.

LAUNDRY MARKER.

Application filed December 19, 1923. Serial No. 681,638.

To all whom it may concern:

Be it known that I, EDWIN LANE, a citizen of the United States, residing at New York, in the county of New York and State of New York, have invented new and useful Improvements in Laundry Markers, of which the following is a specification.

This invention relates to laundry markers for identifying individual pieces or articles and groups of the latter of the same ownership prior and subsequent to launder and dry cleaning operations.

The invention particularly relates to a development or an improvement of the markers disclosed by my pending applications Serial Nos. 681,635, 681,636, and 681,637, all filed Dec. 19, 1923, its general structure being very similar to that of application Serial No. 681,636, wherein an opening device or key is used for separating the normally closed jaws.

In all of my previous structures of laundry markers the jaws are formed with indentations which are produced without separating the metal or material defining said indentations from the jaws. In the present improvement, which is applicable to all of the previous forms, the indentations are separated at the sides and one end of each to provide tongues in one jaw, and in the opposite jaw openings are formed in registering relation to and of slightly greater dimensions than the tongues to permit the portions of the piece or article engaged by the jaws to be pressed into the openings by the tongues to securely hold the marker in connection with the piece or article with less liability of cutting, puncturing or tearing the latter. As a further feature of improvement, the tongues and openings of the jaws are formed in alternate relation in the two jaws so that a part of the tongues are in one jaw between a number of openings in the same jaw and disposed to engage openings in the opposite or second jaw, and the tongues of the latter jaw are arranged to engage the openings in the first jaw to thus produce a reliable interlock of the tongues in relation to the portion of the piece or article engaged by the jaws. A still further feature of the present improvement

is that the tongues and openings in the respective jaws are of different dimensions so as to adapt the tongues and openings for cooperation with light and heavy articles or pieces or articles varying in thickness and weight.

In the drawing:—

Figure 1 is a perspective view of a laundry marker embodying the features of the improvement shown applied to an article or piece and a jaw separating or key device inserted in operative position in the marker.

Figure 2 is a central longitudinal vertical section of the improved marker showing the jaw separating or key device in position therein.

Figure 3 is a bottom plan view of the marker shown applied to a portion of a piece or article.

Figure 4 is a detail perspective view of the jaw separating or key device.

The numeral 5 designates a doubled strip of suitable non-corrosive metal, such as brass or phosphor bronze, bent in such manner as to provide two jaws 6 and 7 which have an overlapping, normally closed relation, as shown, but may be normally open jaws. It is preferred, however, that the jaws have a sufficient resiliency to automatically close the same. A head 8 is formed in rear of the jaws and is wider than the latter, the one member of the head having an identifying number or character 9. The one member of the head in the present instance is also laterally extended, as at 9^a, and formed with a slot or opening 9^b for permitting the marker and the piece or article held thereby to be applied to a hook or other projection for hanging purposes. The jaw 7 is slightly longer than the jaw 6 and both of the jaws have opposed tongues 10 and 11 which are alternately disposed in reverse angular arrangement in the respective jaws and enclosed between the latter, so that the inward maximum projection of the said tongues will alternate, or the projecting portions of the tongues of one jaw will be opposed to or between the projecting portions of the tongues of the remaining jaw. The maximum projections of the tongues 10 and 11

are all directed towards the head 8 and provide a series of transversely extending biting means for reliably holding a portion of an article or piece to be cleaned or laundered.

5 The tongues 10 and 11 are in registering relation with openings 10^a and 11^a formed in the respective jaws and of slightly greater dimensions than the said tongue and whereby the tongues may enter the said openings 10 with clearance and force the portions of the article or piece to which the mark is applied into the said openings. As hereinbefore indicated, the two side edges and one end of each tongue are cut clear of the jaw of 15 which it forms a part and the tongue has sufficient inward projection to extend into the opening with which it is adapted to register. The tongues 10 and openings 10^a in registering relation are larger in dimensions than the tongues 11 and openings 11^a, this being an incidental feature of construction which renders the marker more effective in its application to the article or piece, particularly when the articles or pieces are 25 of material varying in thickness. The present features of the improvement, however, are not confined to this differentiation in dimensions of the tongues and openings in the respective jaws, the essential feature 30 being the tongues of one jaw being free to enter or register with and press a portion of the article or piece into the corresponding openings. As shown by Figure 2, the shorter jaw 6 and the member of the head 35 with which it is continued are inclined inwardly towards the remaining jaw 7 and the remaining member of the head fully from the bend 12, and the member of the head from which the shorter jaw 6 extends 40 at about the point or intersection or termination of the jaw relatively to the head member is formed with a slot or opening 13. In advance of this slot or opening 13 the jaw 6 has an inwardly projecting guard 45 lip or flange 14 which is preferably cut therefrom and has its free end movable and normally in engagement with a slot 15 in the opposite jaw 7. The head member from which the jaw 7 continues is formed with an 50 indentation 16 between the location of the slot 13 and the bend 12 for the purpose of maintaining the opposite members of the head in predetermined spaced relation and to prevent crushing of the head members 55 by pressure stress that may be imposed thereon during the laundering operation. The jaw 7 which is slightly longer than the jaw 6 serves for convenience in applying the marker to a portion of an article or piece to be laundered or dry cleaned, and whereby said projecting portion of the jaw 60 7 may be readily placed under the edge of the article or piece to which it is applied to

guide the said article or piece in between the jaws when the latter are sprung apart.

65

A jaw separating or key device of particular form is shown for operating the jaws, but it will be understood that any suitable device other than the particular form shown may be used. The device as shown 70 is formed with a thumb or finger loop or eye 16^a bent over a flat shank 17 which is straight for a greater portion of its length and in part provides a portion of the wall or defining means for the eye 16 and whereby 75 the device may be held on the thumb or finger of the hand of the operator or assorter without liability of the same turning away from the position desired to be maintained for ready application and practical operation in relation to the marker, as indicated in dotted lines by Figure 1. The free end of the flat shank 17 is bent rearwardly, as at 80 18, and then continued into a terminal angular foot 19, the free extremity of this shank being decreased in width, as at 20, to adapt the same to be readily inserted and removed 85 from the slot 13 and also to give the device freedom of action in performing the function for which it has been devised.

90

The device or jaw separating means is applied to the thumb of the hand of the operator or assorter, as shown by Figure 1, with the angular foot thereof held free for insertion in the slot 18. To apply the improved marker to a portion of an article or a piece to be laundered or dry cleaned, the foot 19 is inserted in the slot 13 and the implement pushed forward until it assumes the position shown by Figure 2 and then turned 95 by the operator who presses inwardly on the device, and the foot 19 acting in conjunction with the bend 21 provided in the formation of the foot and acting as a fulcrum, forces the jaw 6 apart from the jaw 7 to separate 100 the tongues 10 and 11 from the openings 10^a and 11^a to such an extent as to permit the ready insertion of a portion of a piece or article between the jaws or a quick withdrawal of the said portion from the jaws. 110 The portion of the article or piece engaged by the jaws is limited in its rearward movement or cannot pass rearwardly between the members of the head 8 in view of the obstruction provided by the guard lip or 115 flange 14, and the latter also prevents the foot 19 of the opening device from moving forwardly between the jaws and engaging the portion of the article or piece that may be held between said jaws, and as a consequence, the article or piece so held is prevented from being injured or torn by the implement. The opposite members of the head 8 are in such spaced relation that when the reduced end 20 of the shank 17 of the opening device is introduced into the slot 13 the 120 125

bend 21 will bear against the closed portion of the member of the head opposite that having the slot 13 therein, and a turning movement of the reduced end of the opening device will be effected to turn the free end of the foot 19 against that part of the member of the head immediately in advance of the front wall of the slot 13.

The metal of which the marker is formed 10 will be sufficiently resilient to maintain the jaws 6 and 7 normally closed with such force when in engagement with a portion of an article or piece as to prevent accidental disengagement of the marker from the article or piece during launder or dry cleaning operations, but this resiliency of the jaws will be readily overcome in an easy manner through the use of the opening device above explained. It will be understood that markers bearing the same identifying number 20 will be applied to articles or pieces of the same ownership or group, and as the identifying numbers or characters on the markers are readily discernible or easily seen, the several articles or pieces of one group may 25 be expeditiously separated from articles or pieces of another group bearing unlike numbers or characters.

What is claimed as new is:—

30 1. A reusable marker of the class specified consisting of a flat strip of resilient metal doubled on itself to provide a pair of opposed flat jaws both having inwardly projected interacting tongues and registering openings arranged in alternation, the tongues having a rearward reverse angular projecting arrangement in the respective jaws and the free ends of the tongues of each jaw registering with the openings of 35 the opposing jaw, the marker having identifying means and the tongues being blunt and impenetrative, and means for operating the jaws.

40 2. A reusable marker of the class specified consisting of a doubled strip of flat spring metal provided with identifying means and a pair of normally closed jaws, the jaws both being formed with alternately arranged and reverse angularly projected impenetrating tongues, the jaws also having openings in registering relation to and adapted to receive the said tongues.

45 3. A reusable marker of the class specified consisting of a doubled strip of flat spring metal having identifying means and a pair of normally closed jaws, the jaws both being formed with inwardly projecting alternately arranged tongues and registering openings for the tongues, the tongues having a rearward reverse angular projecting arrangement in the respective jaws, the openings being larger in dimensions than the tongues to permit them to force the material engaged thereby into the openings without injury to

the material, and means for opening the jaws.

4. A reusable marker of the class specified composed of a doubled flat strip of spring metal having identifying means and a pair of normally closed resilient jaws, each of the jaws being formed with inwardly projecting alternately arranged tongues and openings to receive the terminals of the tongues, one of the jaws having an inwardly projecting guard and a slot in rear of the tongues and openings and a removable key means insertable through the slot in rear of the guard for springing the jaws apart.

5. A marker of the class specified having an identifying means and a pair of normally closed resilient jaws, the jaws being respectively formed with impenetrative tongues and openings in alternate relation in the two jaws, the tongues and openings varying in dimensions, and means insertable through one of the jaws in rear of the openings and projections thereof for opening the jaws.

6. A reusable marker of the class specified consisting of a doubled flat strip of spring metal and provided with opposed body parts from which continue a pair of normally closed jaws with opposing interacting gripping means arranged in alternation in the respective jaws, the body parts of the marker in rear of the jaw projections being flat and one of the said body parts laterally projected and formed with a slot therein, and means for operating the jaws.

7. A reusable marker of the class specified consisting of a bent flat strip of spring metal having an identifying means and a pair of normally closed jaws having outer smooth sides extending in straight lines from the connecting bend of the jaws, the jaws being formed with inwardly projecting gripping devices having a reverse rearward angular arrangement and disposed longitudinally of and across the jaws within the sides and ends thereof in rows, the jaws also having openings to receive the terminals of the projections, the projections being always confined between the outer sides of the jaws, and means for operating the jaws to open the latter.

8. A reusable marker of the class specified comprising a pair of opposed spring jaws with outer smooth sides extending in straight lines from rear supporting parts thereof, the jaws being normally closed and operable to spring the same apart and having inwardly extending blunt projections and registering openings for receiving the terminals of the projections, the projections having reverse angular directions in the respective jaws, the projections all being confined between the outer sides and ends of the jaws, and means for removably engaging the jaws to separate the latter.

9. A reusable marker of the class specified comprising opposed flat spring metal members having the forward portions thereof arranged to serve as normally closed jaws provided with inwardly extending blunt projections, the projections having reverse angular disposition in the respective jaws and arranged in distinct longitudinal and transverse rows relatively to the jaws and permanently retained in shape, the projections being wholly confined between the outer sides of the jaws and means insertable between the jaws for opening the latter. In testimony whereof I have hereunto set my hand.

EDWIN LANE.
